CLAIM

The ornamental design for the SUV conversion kit, as shown and described.

DESCRIPTION

FIG. 1 is a rear perspective view of the SUV conversion kit showing an exemplary SUV vehicle in phantom lines;

FIG. 2 is a right elevational view thereof with portions of the SUV being shown in phantom lines;

FIG. 3 is a left elevational view thereof with portions of the SUV being shown in phantom lines;

FIG. 4 is a rear elevational view thereof with portions of the SUV being shown in phantom lines;

FIG. 5 is a front elevational view thereof showing the SUV in an outline of phantom lines;

FIG. 6 is a top plan view thereof with portions of the SUV in phantom lines;

FIG. 7 is a bottom plan view thereof showing the outline in phantom lines;

FIG. 8 is a partial rear perspective view with portions of the SUV shown in phantom lines; and,

FIG. 9 is a rear elevational view thereof taken along lines 9-9 in FIG. 6 with portions of the SUV shown in phantom lines. The broken phantom lines depict unclaimed subject matter only and form no part of the claimed design.
